BRAKE SHOE GRINDER

Robert E. W. Harrison and Frederick S. Haas,
Mount Washington, Ohio, assignor to Cincinnati
Grinders Incorporated, Cincinnati, Ohio, a
corporation of Ohio

Application May 14, 1929, Serial No. 363,080

3 Claims. (Cl. 51—108)

This invention relates to improvements in grinding machinery and has particular reference to automatic mechanism for cyclic performance of cylindrical grinding operations.

- 5 One of the objects of the present invention is the provision of an improved mechanism capable of automatic production of arcuate or cylindrical surfaces simultaneously on a series of rings or segmental portions thereof.
- 10 A further object of the invention is the provision of an automatic control mechanism for a grinding machine of the center or work-chucked type which shall effect both the rotation of the work, the relative feed during grinding and the
- 15 retraction and discontinuance of rotation of the work.

An additional object of the present invention is the provision of an improved work holding and driving mechanism which will greatly facilitate the grinding of brake shoe or other segmental members and insure uniformity of size and consequent interchangeability of the several work pieces.

Other objects and advantages of the present invention should be readily apparent by reference to the following specification, considered in conjunction with the appended drawings forming a part thereof, and it will be understood that any modifications may be made in these specific structural details, hereinafter described, within the scope of the appended claims without departing from or exceeding the spirit of the invention.

Figure 1 is a front view of a machine embodying the present invention.

Figure 2 is a top plan view thereof.

Figure 3 is an enlarged fragmentary end view of the work holding member and associated parts with the guard broken away as at line 3—3 of Figure 2.

Figure 4 is a sectional view as on line 4—4 of Figure 3.

Figure 5 is a plan view of one of the work pieces.

45 Figure 6 is a view in elevation thereof.

Figure 7 is a plan view of the automatic cycle control mechanism with the enclosing casing therefor broken away.

Figure 8 is a vertical section as on line 8—8 of Figure 7.

Figure 9 is a section at right angles to Figure 8 on line 9—9 of Figure 7.

Figure 10 is a longitudinal section on line 10—10 of Figure 7, and

Figure 11 is a section through the manual control device on line 11—11 of Figure 9.

In the drawings, in which similar character references are employed to describe corresponding parts throughout the several views, the numeral 15 designates the bed of a grinding machine having rising therefrom the grinder head 16, in which is suitably journaled the grinding wheel spindle 17 bearing a grinding wheel 18. This spindle is suitably driven at a high or grinding rate of speed as from motor 19 and in addition is capable of an axial sliding or reciprocating movement in its bearings, under influence of the spindle oscillator mechanism indicated at 20. It is to be understood that this is preferably a relatively slight movement but serves to break up possible grinding lines on the work and insure a clean finish with minimum and equalized wheel wear.

The bed 15, as indicated in Figure 1, is further provided with ways 21 for the reciprocable carriage 22 bearing the work supporting unit. This unit includes a head 23, which has suitably mounted thereon the work-chuck supporting spindle 24 driven at a slow work revolving rate as from motor 25. This spindle has a plane laterally projecting terminal portion 26 disposed in opposition to the operative face of the grinding wheel 18 and is adapted to receive the sleeve portion 27 of the work holding fixture. This fixture has at one end the terminal flange 28 seating against the rib 29 on the work supporting spindle, the parts being secured in inter-engaged relation as by pin 30 on the spindle, inter-fitting with bayonet slot or groove 31 of sleeve 27.

In the particular form illustrated, sleeve 27 has slidably mounted thereon a series of work clamping discs having central hub portions 32, webs 33 and terminal flanged rims 34. These parts are normally urged into spaced relation by interposed springs 35 but are capable of general retraction for proper clamping of the several work pieces by tightening nut 36 on the end of the sleeve. At suitable points circumferentially of the rims 34, sockets 37 are provided for the spring pressed positioning pins 38. These pins are adapted to seat in the toggle holes 39 of the segmental work pieces which are here illustrated as internal brake shoes having the inner web or flange 40 and the circumferential shoe portion 41 normally contacting, either directly or through intervention of a suitable lining, with the interior of a brake drum. To insure proper operation of the brakes of an automobile, it is necessary that these members be true circular segments as re-

spects the arc position determined in the drum by the toggle or supporting pins fitting in holes 39.

By employment of the present mechanism, these segmental members may be placed in overlying relation to the clamp discs with their webs 40 pressed into spaces between adjacent discs until the positioning pins 38 snap into holes 39, retaining the shoe proper 41 out of contact with the retaining discs. With the parts in this position, tightening of nut 36 causes the clamps to laterally engage the webs of the work pieces so that they are satisfactorily positioned in circumferential relation to the arbor or work supporting fixture and thus to the spindle 26 in a position determined, not by the original general contour of the work piece but determined by the location of the apertures 39, which will similarly subsequently determine the position of the individual work pieces when in use.

In the production of a series of ground work pieces it is desirable that the work supporting spindle be initially located a sufficient distance from the grinding wheel so that the operator may, with safety, remove one work holding fixture and apply another having the rough or unground work pieces thereon. The work having thus been placed in the machine, it is then desirable that the same be rapidly advanced to grinding position, be suitably rotated with a relative feeding movement between the work and grinding wheel for proper stock removal, after which the work should again be withdrawn and its rotation discontinued in order that the operator may remove the completed work and again insert new work to be ground. One mechanism, for automatically controlling the aforesaid cycle of operations, has been illustrated in Figures 7 to 11 inclusive. Carried by the bed 15 is a bracket 42 supporting a housing 43. Journalized within this housing is cam shaft 44 bearing the cam member 45 and the worm gear 46 in driving engagement with worm 47 activated from gearing 48 by control motor 49. Cam 45 is loosely mounted on shaft 44 and coupleable therewith through clutch 50 having a spool portion 51 engaged by shifter arm 52. The arm is intermediately pivoted and has its opposite end riding in groove 53 of sleeve 54 slideable in boss 55 of the casing unit 43. This sleeve is provided with a rack 56 meshing with pinion 57 actuatable by hand lever 58 for retracting or outwardly shifting the sleeve to move clutch unit into operative position to drive the cam 45. Movement in the opposite or declutching direction is automatically effected by means of compression spring 59.

The mechanism here described is intended to function as a single revolution clutch. For this purpose, there is slidably mounted within sleeve 54 a plunger 60 having a detent head 61, which in stop position fits into notch 62 in the face of the cam member and interlocks with the cam to secure same against rotation. When handle 58 is shifted to retract sleeve 54, it carries with it the detent 61, so that the cam is released and clutch 50 engaged. Rotation of the cam carries notch 62 out of alignment with head 61, when the head will ride on the face of the cam, holding the clutch in engaged position until the cam has made a complete revolution, when the detent member will drop back into the notch under influence of spring 59, the clutch being disengaged and the cam rotation positively checked by the detent.

It is to be noted that the plunger 60, itself, is yieldingly mounted in the sleeve and urged

into extended position by spring 63, having a heavier tension than spring 59, so that the detent normally projects. In case of undue resistance to movement of the cam, however, spring 63 will yield, allowing clutch 50 to slip and thus prevent breakage of parts. The plunger is further provided with an extension, as at 64, which serves, as the plunger and sleeve are outwardly moved, to engage switch member 65, completing the circuit between lead 66 and 67 of the drive motor 25 for the work supporting spindle. Consequently, when handle 58 is manually actuated, to initiate rotation of cam 45, switch 65 will also be actuated to start rotation of the work holding spindle. Conversely, when the machine is automatically brought to a stop by movement of detent 61 into notch 62 of the cam, the work drive will be rendered ineffective, spring 65' reversely shifting the switch member 65 so that the work holding arbor member may be readily removed from the machine and a new one substituted.

Cam 45 serves to control the operative association of the work and grinding wheel. This is accomplished through employment of suitable linkage mechanism including an intermediate pivoted rock lever 68, having on one end a pin or roller 69 riding in face groove 70 of the cam and having its opposite end adjustably connected, at 71, with a bell crank type lever 72. Pivoted to one arm of this lever is linkage 73, coupled with slide block 74, in which is journaled adjusting screw 75 in threaded engagement with a bushing 76 carried by the carriage 22. Oscillation of lever 68, as effected by the cam, causes a reciprocation of slide block 74 and thus of the screw and the work carriage. In addition, rotation of the screw by pilot wheel 77 adjusts the position of the work carriage with respect to the block and, thus, the space traversed by reciprocations of the same amplitude, while the adjustment at 71 varies the amplitude of the reciprocations for a given cam contour.

The general outline of the activating cam groove 70 is indicated in Figure 8, from which it will be seen that the cam has a steep accentuated portion, as at 78, for effecting a sharp retraction and, subsequently, a sharp or rapid inward movement of the carriage, this portion controlling the movement of the parts in the work discharging position and initiating their return movement into grinding relation. The cam is further provided with a gradually receding portion, as at 79, controlling the feed or general approach of the work holding unit and grinding wheel for stock removal, followed by substantially concentric portion, as at 80, effecting rotation of the work, without feed, for sparking out grinding to improve the surface and insure final accurate sizing of the parts being produced. This portion 80 merges into the riser 78 for rapid retraction or separation. The riser 78 is disposed in opposition to notch or recess 62, so that, as the lever 68 is swung to its position of maximum retraction, the rotation of the cam and the drive of the work supporting spindle will be automatically discontinued by the mechanism previously described. The machine is then in condition for removal of the holder with series of completed work pieces, and substitution of a new set of pieces to be ground. Inward oscillation of handle 58 will then disengage the cam, couple the clutch thereto for actuation thereof, and complete the work drive circuit for actuation of the work.

While in the present embodiment of the invention, the cam 45 has been shown as connected with carriage 22 to impart a direct reciprocating movement to the carriage for varying the position of the work with respect to the grinding wheel, it could, if preferred, be similarly connected with the grinding wheel, with the work holder spindle, or, the relative approach and separation of the parts could be effected by an oscillatory movement of the grinding wheel or work holder support, under influence of the cam, without appreciably varying the general mechanism or result attained thereby, and these alternatives are therefore reserved as falling within the preview of the present invention.

The operation of the device is as follows: The work rotating and feeding unit is normally in a retracted position, that is, remote from the grinding wheel and with the work carrying spindle quiescent. The sleeve 27 having previously had the work pieces mounted thereon is disposed on the free end of the work spindle and the interlocking pin and slot engaged to prevent disassociation of the sleeve and spindle. The lever or handle 58 is then actuated in a direction to initiate the rotation of the motor 49, and parts operated thereby. This motor rotates the cam 45 and effects the infeed of the work toward the grinding wheel, and at the same time the operation of the handle 58 initiates the rotation of the work carrying spindle. The cam 45 feeds the work into the grinding wheel for a given definite distance, whereupon the work is retracted to its initial loading and unloading position. As soon as the work reaches its retracted position the motor 49 is stopped as well as the cam 45, thereby bringing the parts to a point for a replacement of the work on the work carrying spindle. During the feeding and grinding cycle a second work carrying sleeve 27 is being loaded with work pieces so that as soon as the cycle is complete the operator replaces the sleeve on the spindle with a new one containing the unfinished work pieces. During the operation on the work on the second sleeve the finished work on the first sleeve is removed therefrom and replaced by other unfinished work pieces.

We claim:

1. In a device of the class described the combination of a bed, a pair of spindles journaled thereon having their axes extending parallel to one another and having free ends projecting in the same direction, a grinding wheel secured to the end of one of the spindles, work supporting means detachably secured to the end of the other spindle, means for rotating the grinding wheel at a high rate of speed, means for rotating the work supporting spindle at a relatively slow work rotation speed, means supporting one of the spindles for movement toward and from the other to operatively associate the work and grinding wheel and effect a stock removal from the work including a rotatable cam, a prime mover for rotating the cam, a switch for controlling the work rotation means, a switch plunger operable in one direction to close the switch and release the cam and operable in the other direction for opening the switch and restraining the cam against rotation.

2. In a device of the class described the combination of a bed, a pair of spindles journaled thereon having their axes extending parallel to one another and having free ends projecting in the same direction, a grinding wheel secured to the end of one of the spindles, work supporting means detachably secured to the end of the other spindle, means for rotating the grinding wheel at a high rate of speed, means for rotating the work supporting spindle at a relatively slow work rotation speed, means supporting one of the spindles for movement toward and from the other to operatively associate the work and grinding wheel and effect a stock removal from the work including a rotatable cam, a prime mover for rotating the cam, a switch for controlling the work rotation means, a switch plunger operable in one direction to close the switch and release the cam and operable in the other direction for opening the switch and restraining the cam against rotation.

3. In a device of the class described the combination of a bed, a pair of spindles journaled thereon having their axes extending parallel to one another and having free ends projecting in the same direction, a grinding wheel secured to the end of one of the spindles, work supporting means detachably secured to the end of the other spindle, means for rotating the grinding wheel at a high rate of speed, means for rotating the work supporting spindle at a relatively slow work rotation speed, means supporting one of the spindles for movement toward and from the other to operatively associate the work and grinding wheel and effect a stock removal from the work including a rotatable cam, a prime mover for rotating the cam, a switch for controlling the work rotation means, a switch plunger operable in one direction to close the switch and release the cam and operable in the other direction for opening the switch and restraining the cam against rotation, and additional means operable by the switch plunger for connecting and disconnecting the rotatable cam from the prime mover.

3. In a device of the class described the combination of a bed, a pair of spindles journaled thereon having their axes extending parallel to one another and having free ends projecting in the same direction, a grinding wheel secured to the end of one of the spindles, work supporting means detachably secured to the end of the other spindle, means for rotating the grinding wheel at a high rate of speed, means for rotating the work supporting spindle at a relatively slow work rotation speed, means supporting one of the spindles for movement toward and from the other to operatively associate the work and grinding wheel and effect a stock removal from the work including a rotatable cam, a prime mover for rotating the cam, a switch for controlling the work rotation means, a switch plunger operable in one direction to close the switch and release the cam and operable in the other direction for opening the switch and restraining the cam against rotation, and additional means operable by the switch plunger for connecting and disconnecting the rotatable cam from the prime mover, position means for shifting the switch plunger in one direction and yielding means for shifting the said plunger in the other direction.
